UNITED STATES PATENT OFFICE

FRANK R. HART, OF PACIFIC GROVE, CALIFORNIA

APPARATUS FOR FLUSHING AND DILATING THE URETHRAL CANAL TO FACILITATE THE ADMINISTERING OF RADIANT ENERGY

Application filed January 17, 1929. Serial No. 333,141.

5 My invention relates to a novel apparatus and method for simultaneously dilating, irrigating and administering, germicidal energy, such as the ultra-violet ray, to urethral canals, being an improvement on my co-pending application, Serial No. 176,536, filed March 18th, 1927.

10 The present invention is the outcome of the practice of my above-mentioned invention wherein a still body of water under regulative pressure is used to dilate the urethral canal to facilitate the passage of the violet ray to the posterior cavity of the urethra. In practice I have discovered that it is more advantageous to use a current of water flowing and reflowing through practically the entire urethral length, thus providing means for flushing the canal free of mucous and at the same time providing sufficient resistance to the escape of water to cause an adequate dilation 15 of the urethral canal for its full extent, thus facilitating the application of said ray to the remotest parts of the urethral passage and at the same time permitting the ray to act upon cleansed tissue instead of an accumulation of mucous matter, as is the case when using my former apparatus.

20 I have also found it difficult if not impractical to provide the nicety of water pressure required in such delicate operations when taken under heavy pressure direct from a main water supply.

25 An object therefore of my invention is to provide a means for supplying water to the apparatus under relatively pre-determined volume and pressure, together with the required nicety and gentleness.

Another object is to provide a sanitary apparatus whose parts are readily sterilized.

30 Another very important object of my present invention is to apply a continuous current of fluid, such as water, to the remote end of a urethral canal close to the shut-off muscles, said current being so controlled as to its inlet 35 and outlet that the pressure thereof dilates

the urethral wall sufficiently to admit unimpeded administration of radio-active energy for the full length of the urethra simultaneously with the irrigating, or flushing function performed by the current.

50 A further object is to provide a novel nipple for the apparatus.

Another object is to provide a dished guard-means to prevent the splash of fluid during treatment, and other objects and advantages which will be more fully pointed out in and by the appended claims.

55 Without desiring to limit myself to the precise details illustrated, I have shown two embodiments of my invention in the accompanying drawings in which:—

60 Figure 1 is a side elevational view of my apparatus as attached to an ultra-violet ray machine.

65 Fig. 2 is a front view of the apparatus connected with a water tank.

70 Fig. 3 is a longitudinal mid-sectional view through one form of my improved apparatus taken on the line 2—2 of Fig. 2, plus a diagrammatic, longitudinal, mid-sectional view of a human penis as applied to the apparatus for treatment.

75 Fig. 4 is a detached view of one of the nipples.

Fig. 5 is a similar view to Fig. 3, but shows a different water scheme.

Similar reference characters refer to similar parts throughout the several views.

Having particular reference to the drawings, 5 designates an adapter or container structure adapted for ready attachment to the front A of a ray machine by hand manipulation of the screw 6. The machine with its lens 7 held in place by the bezel 8 forms no part of my invention apart from its function as a source of radio-active energy.

80 The adapter lens 9 is seated in the ground and finished counterbore 10, the gasket means 11 being interposed between said lenses. The barrel 12 is bored in longitudinal alinement 85

90

with the path of the rays, the bore being of sufficient diameter to allow unobstructed passage for the rays, the front of said barrel being provided with the dished guard member 13 and the nipple 14.

5 As shown in Fig. 3 the forward end of the barrel 12 is internally threaded for interengagement with the threaded portion of the nipple 14, said nipple being provided with the flange 14^a to lay hold of when screwing on or unscrewing, and for attainment of a tight joint between said nipple and said guard, the nipple being axially perforated in line with the rays.

10 It is to be understood that said adapter and nipple may be composed of any suitable material and made either separately or in one piece; as shown in Fig. 5, for instance, both said parts could be cast of quartz glass, or the adapter element thereof could be of metal and the nipple element of material penetrable by the ultra-violet ray such as quartz; a quartz nipple would obviously admit of a smaller nipple being used without restricting the field of the rays as would be the case if a metal nipple of relatively small internal diameter were employed.

15 In the form of my invention as embodied in Fig. 3, the wall of the barrel 12 is provided with the upper and lower perforations, 12^a and 19 respectively, the tube 15 furnished with the hose member 21 establishes a fluid communication between the interiors of the tank 22 and the barrel 12. The lower perforation interengages with the internal tube 16 which rises from the point of connection and then turns to the right for a suitable distance in axial alignment with said barrel 12. The end of tube 16 is preferably closed and has 20 the perforation 17 provided adjacent the closed end, which end may be covered with a suitable sheathing 18, similarly closed and perforated to register with the perforation 17. The outlet of the perforation 19 is provided with a drain tube 20.

25 The remote end of the hose 21 connects with the bottom of the tank 22 suspended by the rope 23 passing over the pulley 24 downwardly to a hook 25 on the wall 26, a series of loops as 27, 28 and 29 being provided in said rope for interengagement with the hook 25, or other suitable means to enable the tank 22 to be suspended at various levels. When put in operation the inflow of water soon fills the 30 urethra which causes a reflow through the tube 16, entering said tube by the perforation 17 and escaping by the outlet means 19, which act irrigates and cleanses the tissues of the urethral wall. The ultra-violet 35 energy may or may not be employed at this stage of the treatment. The next step is to raise the tank 22 from loop to loop until the water-pressure distends the urethra to its full extent thus allowing the said rays, now turned on, to exert their germicidal energy

upon the cleansed tissue of the urethral canal and associated tissue.

40 In the second embodiment of my invention, well shown in Fig. 5, the nipple 14 is shown formed integral with the body of the apparatus. The irrigation scheme, while essentially the same in principle, is accomplished by different means; inasmuch as the tube 15 enters the barrel 12 and is bent axially to the right for a suitable distance into the urethra; by this means the water flows back into the urethra within said tube and reflows between said tube and the urethral wall, and escapes through the perforation 19 which is smaller than the intake, therefore adapted to set up fluid pressure within the apparatus.

45 In said first form the inflow is in the direction of said rays and the reflow against said rays, whereas in the second form the relative directions of said rays and said flow are reversed.

50 The feathered arrows indicate the path of the radio-active energy.

55 With regard to the outlet 19 with the extension 20, the latter is preferably a rubber tube which may obviously be choked regulatively by such means as a "Murphy clamp," too well known to need illustration, or by other suitable means.

60 It is believed that the construction, method of operation and advantages of the present invention will now be clearly understood. The two embodiments of the invention have been disclosed in detail by way of example, since in actual practice they attain the features of advantage set forth as being desirable in the statement of the invention and the above description.

65 Numerous changes in the details of construction and arrangement of parts may be resorted to without departing from the spirit or scope of the invention as hereinafter claimed or sacrificing any of its advantages.

70 Having thus described my invention, what I claim as new is:

75 1. In administering apparatus of the kind described, a container structure adapted to co-operate with a source of radiant energy such as an ultra-violet ray machine for the administration of said ray to urethral passages, said container being organically and structurally adapted for passage therethrough of said rays, a nipple carried by the adapter, said nipple perforated to admit passage of fluid therethrough, means to provide a fluid current flowing and reflowing through the urethra, means to restrict said reflow, said means being adapted to dilate said urethral passage.

80 2. In administering apparatus as specified in claim 1, said nipple being provided with a suitably bulbous outer end, a flange, and suitable means for attachment to said container structure.

85 3. In administering apparatus as set forth

in claim 1, regulative means governing the fluid pressure of said flowing and reflowing current.

4. In an apparatus as defined in claim 1, 5 tubular means extending axially back into the urethra, said means perforated adjacent its remote end for the passage of fluid therethrough.

5. In an apparatus as particularized in 10 claim 1, a suitably disposed splash-guard means carried by said apparatus.

In testimony whereof I have hereunto set my hand this 9th day of January, 1929.

FRANK R. HART.
